GAME DEVICE

Reba Burgess Rummel, Grayson, Ky., assignor of
one-half to Adelaide Hockley, Grayson, Ky.

Application May 14, 1938, Serial No. 208,023

4 Claims. (Cl. 273—102.1)

The present invention relates to game devices and embodies a climbing figure toy normally held in a lower position by gravity together with a bucket suspended from a cord trained over a pulley and attached to the figure whereby to raise the figure by the tossing of an object into the bucket.

An important object of the present invention is to arrange a figure toy simulating a mouse adapted to travel upwardly along the surface of a game board into an opening in the board, said opening also serving as a target through which objects may be thrown into the bucket positioned behind the front of the game board to cause the upward movement of the figure.

A further object of this invention is to provide a game of skill of this character of simple and practical construction, which is neat and attractive in appearance, which is amusing and entertaining, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout and in which—

Figure 1 is a front elevational view showing the figure in its lowermost position.

Figure 2 is a similar view showing the figure in its uppermost position.

Figure 3 is a rear elevational view with parts broken away and shown in section.

Figure 4 is a vertical transverse sectional view.

Figure 5 is a top plan view, and

Figure 6 is a perspective view of the shaft for the pulley.

Referring now to the drawings in detail, where in for the purpose of illustration I have disclosed a preferred embodiment of the invention, the numeral 5 designates a game board generally which is preferably of rectangular formation including a front wall 6, rear wall 7 connected by side walls 8 and a top wall 9. The walls, when thus assembled, form a box or housing open at its bottom and having a hanger 10 attached to the top wall 9, which may be of cord, wire or the like, for suspending the game board from a nail or hook 10 attached to a supporting structure whereby to suspend the game board therefrom.

The front 6 is formed with an opening 12 adjacent its upper portion and the top 9 is also formed with an opening 13, the latter being

bridged by a shaft 14, secured to the top as at 15, said shaft having an off-set 16 at its intermediate portion which depends into the opening and upon which a pulley 17 is mounted, the off-set portion in the shaft preventing endwise movement of the pulley on the shaft. 5

Trained over the pulley is a cord or cable 18, one end of the cord being attached to a bucket 19 positioned in the game board, the opposite end of the cord being fed through the opening 12 to a position in front of the game board and to which a figure 20 is attached, said figure preferably simulating a mouse.

The bucket 19 is open at its front side as illustrated in Figure 2 of the drawings, and is of a weight less than the figure 20, whereby the figure will normally pull the bucket upwardly into engagement by a stop 21 positioned inwardly of the game board and which further constitutes a guide for the cord 6, the figure thus occupying a position adjacent the bottom of the game board 20 as illustrated in Figures 1 and 4 of the drawings.

To the front wall 6 of the game board, adjacent its upper portion is secured a circular board 22 decorated to simulate a clock dial having a minute hand 23 and an hour hand 24 pivoted as 25 at 25.

With the device mounted in a position as shown in Figures 1 and 4 of the drawings the purpose of the game is to throw objects of a type indicated at 26 through the opening 12 into the bucket 19, the depositing of a predetermined number of the objects into the bucket causing the weight thereof to move the bucket downwardly pulling the figure 20 upwardly in a manner simulating the Dickery-Dock nursery rhyme. The cord 6 is of sufficient length to enable the bucket 19 to extend downwardly below the lower edge of the game board while the figure partially enters the opening 12 in the manner shown in Figures 2 and 3, whereby the objects 26 may be removed from the bucket, permitting the parts to resume the position shown in Figures 1 and 4. 30 35 40

In playing the game, one player selects the hand 23 whereas the other player selects the hand 24 and is entitled to manually move the hands clock-wise around the face dial to score a point each time sufficient objects 26 are thrown through the opening 12 to cause the upward movement of the figure. 45 50

It is believed the details of construction and manner of use of the device will be readily understood from the foregoing without further detailed explanation. 55

Having thus described the invention, what I claim is:—

1. A game device comprising a game board having an opening therein, a cord movable through the opening, an animal simulating object attachable to the front end of the cord, a receptacle attached to the rear end of the cord and normally held in a raised position immediately behind the opening by the weight of the figure, said receptacle being adapted to receive objects thrown through the opening to offset the weight of the figure and cause an upward movement thereof.

2. A game device of the class described comprising a game board having an opening adjacent its upper portion, a flexible member extended through said opening with its opposite ends positioned respectively in front of and behind the game board, an animal simulating figure attached to the front end of the flexible member, a receptacle attached to the rear end of the flexible member, said figure normally being of greater weight than the receptacle to cause a raising movement of the receptacle and a lowering movement of the figure, stop means at the rear of the game board engageable by the receptacle to anchor the receptacle immediately behind the opening, said receptacle being adapted to receive objects thrown through the opening to offset the weight of the figure and cause a downward movement of the receptacle and an upward movement of the figure.

3. A game device of the class described comprising a game board having an opening adjacent its upper portion, a pulley rotatably supported by the game board above the opening, a flexible member trained over the pulley, one end of said member extending through the opening to a position in front of the board, an animal simulating figure attached to the front end of the flexible member, a receptacle having an open front wall attached to the other end of said flexible member and positioned rearwardly of the game board, the weight of the figure serving to normally urge the receptacle upwardly, stop means carried by the board limiting the upward movement of the receptacle to a position immediately behind the opening, said receptacle being adapted to receive objects thrown through the opening to cause a downward movement of the receptacle and an upward movement of the figure into said opening and suspension means for the game board.

4. A game device simulating the nursery rhyme "Dickery Dock" and comprising an imitation clock, an imitation mouse and mechanism connected to the mouse and operable to cause movement of the mouse relative to the clock, said mechanism including a target actuated by the weight of a missile aimed at the clock and trapped by said target.
